UNITED STATES PATENT OFFICE.

BRUCE F. MORGAN, OF SEATTLE, WASHINGTON.

MECHANICALLY-OPERATED FIGURE TOY.

Application filed February 12, 1925. Serial No. 8,614.

My invention relates to a mechanically operated figure toy. More particularly, my invention relates to a jointed figure in the form of a lumberjack having a saw secured 5 to the arms of said figure, and concealed means to operate said figure.

A primary purpose of my invention is to provide a toy which may be set in motion and be engaged in performing some well-known operation, such as sawing, and at the same time not have the means apparent by which said figure and saw are operated, so that the curiosity of the observer is challenged to understand what makes the device 15 operate.

A further primary purpose is to provide such a toy which will be economical to manufacture and simple in construction, so that it will be characterized by the feature of 20 being free from getting out of order.

The above mentioned objects of my invention, together with others inherent in the same, are attained by the device illustrated in the following drawings, the same being 25 merely preferred exemplary forms of embodiment of my invention, throughout which drawings like reference numerals indicate like parts:

Figure 1 is a view in part section in side 30 elevation of a toy embodying my invention;

Fig. 2 is a plan view of the same;

Fig. 3 is a sectional view on dotted line 3, 3 of Fig. 1;

Fig. 4 is a view of a modified form of resilient means; and

Fig. 5 is a view of a modified form of saw operating means.

A base member 6 is provided with a figure 35 jointed at the hips 8. The arms 9 are pivotally mounted at the sockets 10. Base member 6 is provided with a slot 11 and with a longitudinally disposed opening 12. A saw 13 is pivotally secured to the arms 9 at 14. A resilient means 15 is secured as respects 40 one end portion thereof at 16, the other end of said resilient means being secured to one end of said saw 13. Cord 17 is secured to the saw at 18. A saw retaining member or wedge 19 is disposed in the upper part of 45 said slot 11, whereby the latitude of the movement of the saw is limited, and the impression is given of a regular wedge as used in sawing operations.

The resilient means might be in the form 50 of an elastic band as shown in Fig. 1, or in the form of a concealed spring as shown in

Fig. 4. The means to operate the toy might be of the modified form illustrated in Fig. 5 where rod 20 is pivotally secured to the saw 13. 60

The mode of operation of the device embodying my invention is as follows:

The rear end of the toy may be held close to the body of the operator, so that the cord 17 may be pulled back and forth by the left 65 hand, the toy itself being held by the right hand,—all to the end that the cord 17 does not become visible to the spectator. As the cord is pulled back and forth, it stretches and releases the resilient means 15 with the 70 result that the saw blade pushes the body and arms of the figure 7 up and down, creating the impression that the figure is sawing lengthwise the timber constituting the base member. The retaining member or wedge 75 19 manifestly prevents the saw from being thrown too far upwardly.

Obviously, changes may be made in the form, dimensions and arrangement of the parts of my invention, without departing 80 from the principle thereof, the above setting forth only preferred forms of embodiment.

I claim:

1. A mechanically operated figure toy embodying a figure; a base member upon which 85 said figure is mounted, said base member having a slot therein; a resilient means disposed in said slot and secured to said base member as respects one end portion of said means; a saw pivotally secured as respects 90 one end to the arms of said figure and the other end secured to one end of said resilient means; and a flexible cord connected to one end of said saw.

2. A mechanically operated figure toy embodying a figure, said figure being jointed at the hips and having arms pivotally mounted; a base member upon which said figure is mounted, said base member having a slot 95 therein; a resilient means disposed in said slot and secured to said base member as respects one end portion of said means; a saw pivotally secured as respects one end to the arms of said figure and the other end secured to one end of said resilient means; and a flexible cord connected to one end of said saw. 100

3. A mechanically operated figure toy embodying a figure, said figure being jointed at the hips and having arms pivotally mounted; a base member upon which said figure is mounted, said base member having a slot 110

therein and an opening longitudinally disposed in said base member and intercepting said slot; a wedge member disposed in said slot; a resilient means disposed in said slot 5 and secured to said base member as respects one end portion of said means; a saw pivotally secured as respects one end to the arms of said figure and the other end secured to one end of said resilient means; and a flexible cord secured to one end of said saw.

4. A toy embodying a figure; a base member upon which said figure is mounted, said base member having a slot therein and a recess with which said slot communicates; a 10 saw pivotally secured as respects one end to

the arms of said figure and the other end of said saw disposed in said recess; and means in said recess connected to said saw whereby said saw and figure may be actuated.

5. In combination with a mechanically operated figure toy a base member having an axially disposed recess; a slot longitudinally disposed with respect to said recess and communicating therewith; and a tool member having one end portion concealed and reciprocally movably disposed in said recess. 20 25

In witness whereof, I hereunto subscribe my name this 7th day of February, 1925.

BRUCE F. MORGAN.
